UNITED STATES PATENT OFFICE.

CYRIL WADE-DALTON, OF SALEM, NEW JERSEY.

AUTOMOBILE RADIATOR.

1,409,321.

Specification of Letters Patent. Patented Mar. 14, 1922.

Application filed April 16, 1920. Serial No. 374,381.

To all whom it may concern:

Be it known that I, CYRIL WADE-DALTON, a citizen of the United States, residing at Salem, in the county of Salem and State of New Jersey, have invented certain new and useful Improvements in an Automobile Radiator, of which the following is a specification.

The invention relates to a radiator construction, and more particularly to the class of automobile radiators for the water cooling systems used with internal combustion engines.

The primary object of the invention is the provision of a radiator of this character, wherein the tubes and fins thereof, are detachably secured so that the same can be readily removed without requiring the tearing down or entire disassembling of the radiator, thus permitting the easy and quick repairing thereof, without skilled labor and the placing of new parts therein when the occasion demands.

Another object of the invention is the provision of a radiator of this character, wherein the water tubes are detachably connected in a novel manner to the top and bottom reservoirs, the bottom reservoir being removably fitted in place, and being detachable so that any one or a number of the water tubes can be removed with dispatch, the air fins being mounted upon the water tubes in a novel manner. Thus the radiator in its construction, can be readily and easily assembled and the necessary repairs can be made thereto, resultant from the freezing of the radiator or other damage thereto, and the necessity of the employment of mechanics skilled in radiator construction for the removal of the tubes or fins or other parts thereof, or the placing of the same for assemblage, can be avoided.

A further object of the invention is the provision of a radiator of this character, wherein the fitting of the water tubes in the top and bottom reservoirs thereof, assures tight joints without possibility of leakage between said tubes and reservoirs.

A still further object of the invention is the provision of a radiator of this character, which possesses simplicity in construction, reliability and efficiency in operation, strength, durability, enabling repairs or substitution of new parts to be made with dis-

patch and without necessity of skilled labor, 55 and also which may be manufactured at a minimum cost.

With these and other objects in view, the invention consists in the features of construction, combination and arrangement of parts, 60 as will be hereinafter fully described, illustrated in the accompanying drawings, and pointed out in the claims hereunto appended.

In the accompanying drawings:

Figure 1 is a front elevation of a radiator constructed in accordance with the invention, showing the same removed from the metal housing, employed therewith when assembled within an automobile.

Figure 2 is a side elevation.

Figure 3 is a sectional view on the line 3—3 of Figure 1.

Figure 4 is a sectional view on the line 4—4 of Figure 1.

Figure 5 is a fragmentary sectional view 75 on the line 5—5 of Figure 2.

Figure 6 is a fragmentary plan view of the top tube plate.

Figure 7 is a fragmentary plan view of the bottom tube plate.

Figure 8 is a bottom plan view of one of the water tubes of the radiator.

Figure 9 is a plan view of one of the locking rings for the fastening of the radiator tubes in the bottom tube plate.

Similar reference characters indicate corresponding parts throughout the several views in the drawing.

Referring to the drawings in detail, the radiator comprises an upper or top reservoir 90 A, a lower or bottom reservoir B, the water tubes C arranged between the same, while fitted upon the front and rear water tubes C are the air fins D, the upper or top reservoir A being formed centrally thereof with a filling spout 10, which has a removable cap 11 as usual, and through this spout is adapted to be introduced the water for the filling of the radiator in the ordinary well-known manner.

The upper or top reservoir A is fitted with an upper tube plate 12, formed at its front and opposite ends' edges with an upstanding continuous rim 13, while the rear edge of said plate is formed with a vertical 105 re-inforcing web 14. The reservoir A, which is preferably made from sheet metal, is soldered, brazed or otherwise securely

fastened to the rim 13 and web 14 of the plate 12, which plate constitutes a bottom thereof.

The lower or bottom reservoir B is formed 5 with a laterally extending marginal flange constituting a rim 15, which extends throughout the front, ends and rear edges of the said reservoir and has fitted thereon a lower tube plate 16, which latter is de- 10 tachable and is fastened upon the lower or bottom reservoir B through the medium of removable fasteners 17, which are passed through suitable holes formed in the rim 15, and plate 16 at spaced intervals thereof, 15 so that the said lower plate 16, and lower or bottom reservoir B are separable from each other.

Formed on the top plate 12, and its rear web 14 at the proper point thereof, is an 20 upper hose coupling 18 for the connection of an upper hose with the water jacket of an internal combustion engine and also formed on the lower or bottom reservoir B is the lower hose coupling 19, which is adapted to 25 have connected thereto the lower hose communicating with the water jacket of the internal combustion engine so that the circulation of the water can take place between the radiator and said water jacket in the 30 usual well known manner.

The lower hose coupling 19 has fitted therein a valve drain cock 20, of any ordinary well-known construction, which, when open will permit the draining of the radiator, and also the water jacket of the internal 35 combustion engine.

The upper tube plate 12 has formed therein rows of spaced threaded openings 21, for the detachable engagement of the upper 40 threaded ends 22 of the water tubes C which are disposed vertically between the upper or top reservoir B, the lower ends of said water tubes 22 being formed with circular terminals or disk-like heads 23, each being 45 provided with a squared center opening 24, to accommodate a tool such as a plug wrench so that each tube can be turned for the engagement of the threaded end 22 thereof, in the companion threaded opening 21, in the 50 upper tube plate 12, and this particular terminal or head 23, forms an abutment for the water tube C with the lower tube plate 16 in a manner and for a purpose presently described.

55 The lower tube plate 16, has formed therein rows of spaced non-threaded openings 25 which are adapted to vertically align or register with the openings 21 in the upper plate 12, and through said openings 25, in the 60 plate 16 are adapted to be passed the water tubes C which are slidable through said openings 25. Each opening 25 merges into a threaded counterseat 26, the latter being formed in the lower portion of said plate 16, 65 while the opening 25 is formed in the upper

portion thereof and engageable in this threaded counter-seat 26 is a threaded locking ring 27, formed with spanner wrench engaging sockets 28 so that a spanner wrench can be used for the engagement of the locking rings 27 in the counter-seats 26 to securely fasten the tubes removably engaged in the openings 25 in the lower plate 16, the circular terminals or disk-like heads 23 being confined in the counter-seats 26 to about 70 the plate 16 at the shoulders 29 between the openings 25 and counter-seats 26 in said plate. It is of course understood that suitable washers or packing can be arranged between the shoulders 29, and circular terminals or heads 23 to assure a water-tight joint between the tubes C and the lower reservoir B of the radiator.

Arranged vertically approximately centrally of the upper or top reservoir A, and rising within the filling spout 10 thereof, is an over-flow tube 30, which has its lower end suitably fitted in one of the water tubes C in vertical alignment therewith, while in the lower or bottom reservoir B is another 90 tube section 31, which extends through said reservoir B and is held fast therein by a lock nut 32, which pipe section 31 forms a continuation of the water tube C with which is connected the over-flow pipe 30, so that 95 any over-flow from the radiator will discharge from the upper or top reservoir A through pipe 30, the water tube C connected therewith and the pipe section 31 exteriorly of the lower or bottom reservoir B as will 100 be clearly apparent.

The air fins D include front and rear horizontally disposed strips 33, and vertical connecting pieces 34, the strips and pieces being spaced apart and soldered or otherwise connected together. Each of the horizontal strips 33 is formed with notches or recesses 35 which are spaced apart and are adapted to accommodate certain of the water tubes C, while these strips are also 105 provided at intervals with perforated ears 36 through which are loosely passed certain other of the water tubes C so that the air fins D, including the strips 33 and web 34 united together, can be removably connected 110 with selected water tubes C, whereby on detaching said selected water tubes from the radiator, the air fins D can be separated from the latter.

It will be apparent that any one, several, 120 or all of the water tubes C can be removed from the radiator by detaching the lower or bottom reservoir B from the lower tube plate 16, and thereafter removing the locking rings 27, from the counter-seats 29, in 125 said plate, whereupon a plug wrench or other like tool can be engaged with the water tube C to be detached or removed by the turning of the latter so as to disengage its upper threaded open end 22, from the up- 130

per tube plate 12. On disengaging the upper end 22 of the water tube C from the upper tube plate 12, the said water tube C can be removed by sliding it through the 5 opening 25 in the lower tube plate 16, and thus disengaging the said water tube.

It is obvious that the necessity of entirely tearing down or disassembling the radiator is eliminated when repairs to the water tubes 10 C or the substitution of new water tubes is required, as the damaged water tube or tubes can be readily removed from the radiator, it being also apparent that other repairs can be made to the radiator when the occasion 15 requires as all parts thereof are separable from each other, and readily accessible.

It is to be understood that the size of the water tube C can be varied and also the radiator in its entirety can be increased or 20 decreased in size to adapt the same to variable types of pleasure or commercial automobiles.

A suitable gasket 37 is employed between the lower or bottom reservoir B and the 25 lower tube plate 16, to avoid any leakage in the jointure of said reservoir and plate.

Changes, variations and modifications may be made in the invention, as come properly within the scope of the appended claims 30 without departing from the spirit of the invention or sacrificing any of its advantages.

From the foregoing, it is thought that the construction and manner of assemblage and disassemblage of the radiator and the operation thereof will be clearly understood and therefore a more extended explanation 35 has been omitted.

What is claimed is:

1. A radiator construction of the character described, comprising top and bottom reservoirs, an upper water tube plate carried by the top reservoir and having 40

threaded openings therein, a bottom water tube plate detachably connected with the bottom reservoir and having inner non-threaded 45 openings therein, a plurality of water tubes slidable through the non-threaded openings in the bottom plate and having threaded upper ends for detachable engagement in the threaded openings in the top plate, detachable countersunk locking means engageable with the bottom plate for securing the tubes in the non-threaded openings in said bottom plate, a front and rear series of independent air fins detachably connected with 55 certain of the water tubes and connecting webs between the air fins for uniting the same together.

2. In a radiator of the character described, a plurality of water tubes, each formed with 60 a headed lower end and a threaded upper end, upper and lower water tube plates, the upper water tube plate being formed with threaded openings for detachably receiving the upper threaded ends of said tubes, the 65 lower water tube plate being formed with non-threaded openings for loosely receiving the headed lower ends of the water tubes, said lower water tube plate being formed with threaded counter-seats, registering with 70 the non-threaded openings therein, countersunk locking rings detachably engaging in the threaded counter-seat to fasten the headed ends of the water tubes in the lower water tube plate, an upper water reservoir carried 75 by the upper tube plate, a removable lower reservoir carried by the lower tube plate, and a series of independently secured air fins removably connected with certain of the water tubes.

In testimony whereof, I affix my signature hereto.

CYRIL WADE-DALTON.
